 3 Claims. (Cl. 260—268)

This invention relates to new organic compounds. More particularly, it relates to piperazincarboxylic acid esters and salts thereof.

The novel compounds of this invention are the lower alkyl esters (particularly methyl and ethyl esters) of 4-(3'-dimethylaminopropyl)-1-piperazincarboxylic acid and the non-toxic acid addition and quaternary salts thereof.

The free bases of the compounds of this invention are liquids or low melting solids. They are basic in character and form dibasic acid addition salts with acids such as hydrochloric, hydrobromic, sulfuric, acetic, citric, tartaric, lactic, succinic, maleic, phosphoric, malic, gluconic, ascorbic, 1,1'-methylene-bis-(2-naphthol-3-carboxylic acid), butane-1,2,3,4-tetracarboxylic acid and the like. It is more convenient to store and use these compounds in the form of the salts rather than as free bases.

Lower alkyl 4-(3'-dimethylaminopropyl)-1-piperazincarboxylate of the invention may be prepared by reacting 1-carb(lower alkoxy)piperazine with 1-chloro-3-dimethylaminopropane, a commercially available reagent. Specifically the compounds of this invention may be prepared from methyl 1-piperazincarboxylate or ethyl 1-piperazincarboxylate, the latter a commercially available reagent. The reaction is carried out by conventional techniques, usually sodium methoxide, potassium carbonate, sodium bicarbonate or the like, acting as acid binders in refluxing ethanol, β -methoxyethanol, benzene or the like as solvent. Ordinarily no effort is made to isolate the product as a free base. Hydrogen chloride is added to the crude product, and the purified product is then recovered, after recrystallization if necessary, as a dihydrochloride.

The compounds of this invention show antiviral activity in vivo in warm blooded animals. Thus, for example, ethyl 4-(3'-dimethylaminopropyl)-1-piperazincarboxylate shows a definite and reproducible protective effect in experimental influenza virus infections in mice. The results of tests on experimental influenza virus infections are summarized in the following Tables I to IV.

TABLE I.—EFFECT OF TREATMENT WITH ETHYL 4-(3'-DIMETHYLAMINOPROPYL)-1-PIPERAZINECARBOXYLATE DIHYDROCHLORIDE ON SURVIVAL OF MICE INFECTED WITH INFLUENZA A (PR-8)

Treatment Each Dose (mg./kg.)	Alive/Total (Percent Survivors) on 21st Day After Infection	
	Treatment Route	
	Subcutaneous	Oral Tubing
1,600	2 54/120 (45)	2 25/59 (42)
800	2 29/120 (24)	17/60 (28)
400	1 11/100 (11)	1/20 (5)
200	2 13/100 (13)	1/20 (5)
100	1/39 (3)	
15 Saline Treated Infected Controls	2/100 (2)	8/60 (13)

Animals: Taconic Farms, male albino mice weighing 20 ± 2 grams each. Infection: Influenza A (PR-8 strain); 0.05 ml. of a $10^{-6.5}$ dilution of the supernate of a 10 percent (W/V) homogenized PR-8 virus infected mouse lung suspension suspended in sterile brain heart infusion broth; intranasally.

Treatment: Indicated dose dissolved in 0.85% NaCl solution given at the time of infection; and at 24 and 48 hours after infection.

¹ Significantly different from controls at 5% level.

² Significantly different from controls at 1% level.

The above results show that at 800 mg./kg. subcutaneously the mice survival is twelve times that of the controls.

TABLE II.—EFFECT OF NUMBER OF DOSES AND SCHEDULE OF ADMINISTRATION OF ETHYL 4-(3'-DIMETHYLAMINOPROPYL)-1-PIPERAZINECARBOXYLATE DIHYDROCHLORIDE ON SURVIVAL OF MICE INFECTED WITH INFLUENZA A (PR-8 STRAIN)

Number of Oral Doses Given 24 Hour Intervals	Time Treatment Initiated Relative to Infection					
	-24 Hours		0 Hour		+24 Hours	
	A/T ^a	Percent Survivors	A/T	Percent Survivors	A/T	Percent Survivors
1	5/40	12.5	9/40	22	5/40	12.5
2	8/40	20	6/40	15	5/40	12.5
3	36/80	45	17/40	42.5	13/80	16
None, infected controls			5/80	6		

^a A/T = Alive/total on 21st day after infection (total of 2 to 4 experiments).

Animals: Taconic Farms male albino mice weighing 20 ± 2 grams. Infection: Influenza A (PR-8 strain); 0.05 ml. of a $10^{-6.5}$ dilution of the supernate of a 10 percent (W/V) homogenized PR-8 infected mouse lung suspension in sterile brain heart infusion broth; intranasally.

Treatment: Each dose of 1,600 mg./kg. dissolved in 1 ml. 0.85% NaCl given orally at indicated time and, in the case of more than one dose, at 24 hour intervals thereafter.

TABLE III.—EFFECT OF TREATMENT WITH ETHYL 4-(3'-DIMETHYLAMINOPROPYL)-1-PIPERAZINECARBOXYLATE DIHYDROCHLORIDE ON SURVIVAL OF MICE INFECTED INTRANASALLY WITH VARIOUS STRAINS OF INFLUENZA VIRUS

Dilution of Infection Challenge	Influenza A PR-8 Strain		Influenza A J305 Strain		Influenza B Lee Strain	
	Treated A/T ^a	Control A/T	Treated A/T	Control A/T	Treated A/T	Control A/T
10 ⁻⁴			5/80	6/80	0/20	0/20
10 ^{-4.5}			2 21/60	8/60		
10 ⁻⁵	0/60	0/60	2 75/100	39/100	4/80	1/80
10 ^{-5.5}	0/60	0/60	16/20	16/20	2 26/60	8/60
10 ⁻⁶	2/80	1/80	10/10	10/10	1 51/60	39/59
10 ^{-6.5}	2 31/80	14/80				

^a A/T = Alive/total on 21st day after infection.

Animals: Taconic Farms male albino mice weighing 20 ± 2 grams.

Treatment: 800 mg./kg. subcutaneously at time of infection, at 24 hours and at 48 hours after infection.

Infection: 0.05 ml. of indicated dilution of the supernate of 10% (W/V) homogenized infected mouse lung suspension in sterile brain heart infusion broth.

¹ Significant difference at 5% level.

² Significant difference at 1% level.

TABLE IV.—EFFECT OF METHYL 4-(3'-DIMETHYLAMINOPROPYL)-1-PIPERAZINECARBOXYLATE DIHYDROCHLORIDE ON SURVIVAL OF MICE INFECTED WITH INFLUENZA VIRUS

Treatment	Survival on 14th Day				
	1st Test	2nd Test	3rd Test	Combined Tests	
				Survivors/Total	Percent Survival
Cl 53,100 Controls (0.85% NaCl)	2/10 1/20	3/5 1/15	3/10 0/20	8/25 2/55	32 4

Animals: Taconic Farms male white mice, 19-25 grams body weight. Infection: Intranasal; 0.05 ml. of a $10^{-6.3}$ dilution in brain heart infusion broth of stock Influenza A (PR-8 strain) virus.

Treatment: Compound was administered subcutaneously in three doses of 1,600 mg./kg. each dissolved in 0.5 ml. of water, immediately after infection and at 24 and 48 hours after infection. Controls received 0.5 ml. of 0.85% NaCl solution.

The combined tests show that 8 times as many mice survived when given the drug over survival of controls.

The compounds of the present invention described may be dispensed in compositions comprising the active ingredient and excipients including a carrier. While the amount of active ingredient to be given daily will depend on many factors such as the size, weight, age, kind and severity of infection, etc. of the warm blooded animal, a daily intake ranging from 5 to 1000 milligrams per kilogram of body weight will produce good results. The dosage unit may vary from 0.05 to 2 grams and may be in a form to be administered one or more times per day, or in smaller forms for multiple daily, or other more frequent administration. Any of the usual dosage unit forms of pharmaceutical compositions can be useful, for example, tablets, oblets, hard or soft shell capsules, parenteral solutions or suspensions, oral solutions or syrups, etc.

Tablets or oblets may include, in addition to active ingredients, any of the following excipients. A binder such as acacia, corn starch, gelatin, or the like. A disintegrating agent such as corn starch, potato starch, alginic acid, or the like. A lubricant such as stearic acid, magnesium stearate, talc or the like. Also, a sweetening agent as saccharin or sucaryl, and/or a flavoring such as peppermint oil, oil of wintergreen or orange or cherry flavoring can be used.

Capsules may include, in addition to active ingredient, a lubricant and also an inert filler such as lactose, sucrose, corn starch or the like.

Solutions, usually include an acid such as hydrochloric, citric, tartaric, succinic, maleic, ascorbic, phosphoric or the like, or a suitable buffer thereof. Suspensions include a surfactant such as polyoxyethylene sorbitan monooleate (a complex mixture of polyoxyethylene ethers of mixed partial oleic esters of sorbitol anhydrides); oxyethylated tertiary octylphenol formaldehyde polymer; p-isoctylpolyoxyethylenephenol polymers or the like; a suspending agent such as polyethylene glycol 4000 USP (a condensation polymer of ethylene oxide and water, represented by the formula: $\text{HOCH}_2(\text{CH}_2\text{OCH}_2)_n\text{CH}_2\text{OH}$, wherein n varies from about 70 to 85, the molecular weight being about 4000), carboxy methylcellulose (sodium carboxymethylcellulose, USP, the sodium salt of a carboxymethyl ether of cellulose having a closely controlled number of sodium carboxymethyl

($-\text{CH}_2\text{COONa}$)

groups introduced into the cellulose molecule to bring about solubility in water); methylcellulose (cellulose methyl ether prepared from wood pulp or chemical cotton by treatment with alkali and methylation of the alkali cellulose with methyl chloride), and the like; and a buffer such as a phosphate, citrate, or tartrate buffer. Both solutions and suspensions may include a stabilizer such as disodium salt of ethylene-diaminetetraacetic acid,

sodium sulfite, monothioglycerol, or the like; and a preservative such as benzyl alcohol, parabens (methyl and propyl esters of p-hydroxybenzoic acid), or the like.

Oral solutions may include a suspending agent or viscosity control such as magnesium aluminum silicate, carboxymethylcellulose or the like as well as a buffer, preservative, etc. Solutions and suspensions may be of the aqueous sugar or sorbitol type. It is also known in pharmaceutical practice to employ a propylene glycol type solvent for use with drugs.

The invention is further illustrated by means of the following examples.

EXAMPLE I

Preparation of ethyl N-(3'-dimethylaminopropyl)-1-piperazinecarboxylate dihydrochloride

To a round bottom flask is added 420 g. (2.66 moles) of 3-dimethylaminopropylchloride·HCl and 158 g. (1.0 mole) of ethyl 1-piperazinecarboxylate in 1 liter of ethanol

The reaction mixture is heated in refluxing conditions and a solution of 217 g. (4.03 moles) of sodium methylate in 2 liters of ethanol is added over a period of 30 minutes. The mixture is heated under refluxing conditions for an additional hour and cooled to 10-20° C. The precipitated salt is collected by filtration and the filtrate concentrated to a residue. The residue is dissolved in 500 ml. of water, the solution adjusted to pH 13.5 with potassium hydroxide pellets, saturated with potassium carbonate and extracted with 3 x 500 ml. portions of ethyl ether. The combined ether extracts are dried over magnesium sulfate, filtered and the product precipitated with an alcoholic hydrochloric acid. The yield is 113 g. 35.8%, melting point 243-248° C. A sample analytically pure had a melting point of 251-253° C.

EXAMPLE II

Preparation of methyl 4-(3'-dimethylaminopropyl)-1-piperazinecarboxylate dihydrochloride

To a solution of 20.7 g. (50 mmoles) of 1-(3-dimethylaminopropyl)-piperazine with 150 ml. 1 N sodium hydroxide is added, simultaneously, 7.1 g. (75 mmoles) of methyl chloroformate and 112.5 ml. of 2 N sodium hydroxide. After stirring for one hour, solid potassium carbonate is added, to near saturation, and the mixture is extracted with two 250 ml. portions of chloroform. The extract is dried over anhydrous magnesium sulfate, and stripped of solvent at the water pump. A solution of the residual oil in 2β alcohol is heated with 25 ml. of saturated alcoholic hydrogen chloride. The white solid (14.2 g.) is recrystallized twice from methanol, giving 8.3 g. (55%) of analytically pure product, melting point 237° C., dec.

EXAMPLE III

The compounds of this invention may be dispensed in hard or soft shell capsules. A useful formulation for preparing such capsules is as follows.

Methyl 4-(3'-dimethylaminopropyl)-1-piperazinecarboxylate dihydrochloride ----- 25.0
Magnesium stearate ----- 0.1250
Mix thoroughly and dispense in 50 capsules.

EXAMPLE IV

The compounds of this invention may be dispensed as pharmaceutical tablets or oblets. A useful formulation for preparing tablets or oblets is as follows.

Per tablet, g.
Ethyl 4-(3'-dimethylaminopropyl)-1-piperazinecarboxylate dihydrochloride ----- 50.0
Corn starch ----- 2.0
Methyl cellulose (viscosity, 400 cps.) ----- 0.50
Magnesium stearate, 1% ----- 0.525
Mix thoroughly and dispense as 100 tablets.

The above tablets each containing 0.5 g. of active ingredient may be considered to provide an entire single daily dose. Such a tablet might be scored so as to provide fractional daily doses. Alternatively, tablets containing smaller amounts of active ingredient might be prepared for fractional daily or smaller doses.

We claim:

1. A lower alkyl ester of 4-(3'-dimethylaminopropyl)-1-piperazinecarboxylic acid and non-toxic acid addition and quaternary salts thereof.
2. The compound methyl 4-(3'-dimethylaminopropyl)-1-piperazinecarboxylate.
3. The compound ethyl 4-(3'-dimethylaminopropyl)-1-piperazinecarboxylate.
